CLAIM

The ornamental design for a dual eye shield, as shown and described.

DESCRIPTION

FIG. 1 is a perspective view of a dual eye shield showing my new design;

FIG. 2 is a front elevation view of FIG. 1;

FIG. 3 is a top plan view of FIG. 1; and,

FIG. 4 is a side elevation view of FIG. 1.

The broken lines in the drawings depict environmental structure and form no part of the claimed design.
